UNITED STATES PATENT OFFICE.

GEORGE M. MITCHELL, SR., OF PATERSON, NEW JERSEY.

STRAP-WRENCH.

1,161,402.

Specification of Letters Patent. Patented Nov. 23, 1915.

Application filed October 6, 1915. Serial No. 54,333.

To all whom it may concern:

Be it known that I, GEORGE M. MITCHELL, Sr., a citizen of the United States, residing at Paterson, in the county of Passaic and 5 State of New Jersey, have invented certain new and useful Improvements in Strap-Wrenches, of which the following is a specification.

This invention consists in a tool for use 10 in turning pipes or other threaded parts in coupling or uncoupling them, and its object is to provide a tool of this class which, while adapted to avoid abrading, crushing or otherwise injuring the part to be turned, 15 will serve to obtain a powerful non-slipping grip on the same, may be readily applied to or removed therefrom, and will be capable of a wide range of easily effected adjustments.

20 In the accompanying drawing, Figure 1 is a side elevation of the improved wrench; Figs. 2 and 3 are front and rear elevations thereof, the strap being removed in Fig. 3; Fig. 4 is a vertical sectional view of the 25 strap-holding portion of the leverage member, the movable parts *i* and *n* thereof being removed; Figs. 5 and 6 are sectional views of such parts.

The leverage member includes the body 30 part or frame *a*, which in the present case is fork-shaped, and the handle *b*, which at *c* is threaded and tapped into the neck or yoke *d* of the part *a* so as to turn freely therein when the lock-nut *e* thereon, adapted 35 to bind against said neck or yoke, is released. The arms *a'* of the part *a* are connected by the rigid cross-sectionally triangular abutment *f*, which is preferably concave on the side thereof adjacent the neck or yoke 40 *d* but flat on the opposite side, the latter side being inclined upwardly from front to rear; they may also be strengthened by the integral web *a*² connecting them at the front. Said arms have below and above the abutment *f*, respectively, the pairs of longitudinal slots *g* *h*. Said leverage member also includes the jaw *i* fitted between the arms *a'* of the part *a* and having opposite studs *j* which are received by the slots *g*; the face 45 of the jaw adjoining the abutment *f* is convex and at its opposite side it has a circumferentially grooved stud *k* received by a socket *l* in the end of the handle *b* with which, by virtue of a screw *m* tapped into 50 the handle and engaging in said groove, it is swiveled. Said leverage member further

includes the movable head *n* which in the present case is a block arranged to slide longitudinally of and in the frame *a* between the arms *a'* thereof and having opposite studs *o* received by the slots *h*. The side of the head *n* adjoining the abutment *f* is inclined so as to be substantially parallel with the inclined face of said abutment, whereas its opposite face *n'* is preferably flat 35 and perpendicular to the axis of the leverage member and is adapted to project from the free end of the frame *a* in any position to which said head is slidable therein. Said head *n* in the present instance is prevented 70 from canting in the frame by bearing against the web *a*².

p is a suitable form of flexible gripping device herein termed a strap and actually shown as a strap or band, as of leather, duck 75 or the like. It is formed with a bight *q* adapted to embrace and grip the pipe *A*, or other part to be turned, such bight being adapted to rest upon face *n'* of head *n*, while the ends of the strap are extended over the 80 rear face of the head *n* and then between the abutment *f* and said head, one such end *p'* being left free and the other *p*² extended between the jaw *i* and the abutment.

In using the tool, having secured end *p*² 85 of the strap against slippage by extending it through the frame *a* around the triangular abutment *f*, then screwing up the handle to cause the said end to be gripped by and between the jaw *i* and the abutment and finally 90 binding the handle against turning by setting the lock-nut *e* against the frame, the strap *p* is passed around, and formed with the bight *q* to embrace, the pipe *A* to be turned, whereupon its other end *p'* is extended between the head *n* and the end *p*² 95 of the strap and drawn up tight, in such manner, however, that the leverage member will stand substantially perpendicular to the pipe. The relation of the thus-assembled 100 leverage and strap members to the pipe at this time is shown in Fig. 1. When the leverage member is now turned in the direction of the arrow in Fig. 1, the first part of the movement is a movement lever-fashion 105 of said member on the pipe as a fulcrum and relatively thereto, resulting in head *n* being forced toward the abutment and the strap ends being so securely clamped by and between them as to effectively prevent slippage of either; when head *n* ceases to yield 110 further under the pressure continued move-

ment of the leverage member in the direction of the arrow results primarily in the strap member tightening and thus obtaining an effectual friction grip on the pipe and 5 thereupon in the latter yielding to the turning influence of the implement. The return movement of the implement (reverse to the arrow) is obviously characterized by the perfectly free slippage of the strap upon 10 the pipe A.

It may be remarked that while I preferably provide some means to attach the strap member to the handle member so that it may always be kept connected therewith and the 15 strap may be taken up or let out to suit pipes having different diameters, such as the means f_i , I do not wish to be limited to the employment of any such means auxiliary to the means f_n , which it will be obvious effects clamping pressure on the end p^2 as well as the end p' of the strap. On the other hand, I do not wish to be limited to such means f_n clamping both ends of the 20 strap, because so long as the leverage member is adapted in whatsoever manner to hold one end of the strap against slippage and the other end remains to be clamped by the means f_n an operative and effective implement results.

Having thus fully described my invention, what I claim as new and desire to secure by Letters Patent is:—

1. In a wrench, a leverage member having means to hold against slippage both ends of 35 a strap, said means including an abutment and a head freely movable toward and from the abutment and forming with the latter a clamp, in combination with such strap, the latter having a bight therein resting against 40 the side of said head remote from the abutment and adapted to grip the part to be turned and also having one of its ends interposed between said head and abutment and adapted to be clamped thereby.

2. In a wrench, a leverage member having 45 means to hold against slippage both ends of a strap, said means including an abutment

and a head freely movable rectilineally toward and from the abutment and forming with the latter a clamp, in combination with 50 such strap, the latter having a bight therein resting against the side of said head remote from the abutment and adapted to grip the part to be turned and also having one of its ends interposed between said head and abutment and adapted to be clamped thereby.

3. In a wrench, a leverage member having means to hold against slippage both ends of a strap, said means including an abutment and a head freely movable toward and from 60 the abutment and forming with the latter a clamp, in combination with such strap, the latter having a bight therein resting against the side of said head remote from the abutment and adapted to grip the part to be 65 turned and also having both of its ends interposed between said head and abutment and adapted to be clamped thereby.

4. In a wrench, a leverage member having an abutment and a head movable toward 70 and from the abutment and forming therewith a clamp, in combination with a strap having one end thereof longitudinally adjustably secured to the leverage member and also having a bight resting against the side 75 of said head remote from the abutment and adapted to grip the part to be turned, said strap having its other end interposed between said head and abutment and adapted to be clamped thereby.

5. In a wrench, a leverage member having an abutment and a head movable toward and from the abutment and forming therewith a clamp, in combination with a strap having 80 a bight resting against the side of said head 85 remote from the abutment and adapted to grip the part to be turned and one of its ends interposed between said head and abutment and adapted to be clamped thereby, said member also having means, coactive 90 with the abutment, to adjustably grip the other end of the strap.

In testimony whereof I affix my signature.

GEO. M. MITCHELL, Sr.
